COMBINED PORTABLE HARMONICA HOLDING
MICROPHONE AND RADIO TRANSMITTER
OR SIMILAR ARTICLE

Frank J. Forey, 3057 Leeward Ave.,
Los Angeles, Calif. 90005

Filed Dec. 16, 1968, Ser. No. 15,000

Term of patent 14 years

Int. Cl. D14—03

U.S. Cl. D56—1

FIG. 1.

FIG. 2.

FIG. 5.

FIG. 4.

FIG. 3.

FIG. 1 is a front, top and right side perspective view of a combined portable harmonica holding microphone and radio transmitter or similar article, showing my new design;

FIG. 2 is a front elevational view;

FIG. 3 is a left side elevational view;

FIG. 4 is a rear elevational view; and

FIG. 5 is a bottom plan view thereof.

A broken line showing of a representative harmonica in FIGS. 3 and 5 is for illustrative purposes only.

I claim:

The ornamental design for a combined portable harmonica holding microphone and radio transmitter or similar article, as shown and described.
